DESIGN FOR A JET MOTOR CAP

Harry Wurth Morgan, Pasadena, Calif., assignor
to Aerojet Engineering Corporation, Pasadena,
Calif., a corporation of Delaware

Application June 5, 1943, Serial No. 110,377

Term of patent 14 years

(Cl. D71—1)

To all whom it may concern:

Be it known that I, Harry Wurth Morgan, a citizen of the United States, residing at 1200 Lida Street, Pasadena, in the county of Los Angeles and State of California, have invented a new, original, and ornamental Design for a Jet Motor Cap, of which the following is a specification, reference being had to the accompanying drawing, forming part thereof.

Fig. 1 is a side perspective view of a jet motor cap showing my new design; and

Fig. 2 is a top plan view of the jet motor cap shown in Fig. 1.

I claim:

The ornamental design for a jet motor cap, substantially as shown.

HARRY WURTH MORGAN.
